BATCH-MEASURING DEVICE FOR FEEDING
MATERIALS TO CURB PRESSES

Howard F. MacMillin, Mount Gilead, Ohio, assignor to The Hydraulic Press Corporation, Inc., Wilmington, Del., a corporation of Delaware

Application April 8, 1936, Serial No. 73,332

7 Claims. (Cl. 221—112)

This invention relates to feeding and charging devices, and especially to devices adapted for feeding measured quantities of materials to various apparatus. In the present embodiment the charging device is particularly adapted for feeding materials to curb presses, such as are used for extracting oil from animal or vegetable matter.

One object of this invention is to provide a batch-measuring and feeding device, wherein the measuring members are actuated alternately by fluid pressure means.

Another object is to provide a feeding and charging device, wherein a pair of moving members, such as slides, are operated alternately by fluid pressure cylinders which are interconnected by conduits so that one piston is operating in one direction while the other piston is operating in the opposite direction.

Another object is to provide a feeding and charging device of the above description, wherein means is provided for bringing the pistons to a gradual halt without sudden jars or jolts of the mechanism.

In the drawings:

Figure 1 is a central vertical section through the batch-measuring and feeding device of this invention, taken in the plane of the actuating piston rods.

Figure 2 is a plan view of the apparatus shown in Figure 1.

Figure 3 is a side elevation of the apparatus shown in Figure 1.

Figure 4 is a transverse vertical section along the line 4—4 in Figure 1.

Figure 5 is a fragmentary central vertical section through the plane of the actuating piston rods, taken in the opposite direction from Figure 1.

Referring to the drawings in detail, Figure 1 shows the feeding and charging device of this invention as consisting of a casing 10, of approximate cylindrical form, having a cylindrical bore 11 therethrough. The bottom of the casing 10 is provided with a flange 12, whereby the entire device may be secured, as by the bolts 14, to the head 13 of the apparatus to which the materials are to be fed in measured charges. The apparatus may, for example, consist of a curb press for compressing quantities of vegetable or animal matter so as to extract the oil therefrom. It is preferable in such presses to insert these materials in measured charges and thereby economize in the operation of the press.

The casing 10 is likewise provided with an

upper flange 15, to which a funnel may be attached if desired, in order to assist the filling of the device. The casing 10 within the bore 11 is provided with grooveways 16, of a roughly V-shaped cross section. These grooveways 16 pass half-way around the interior of the bore 11, and serve for the guidance of measuring slides 17 and 18. The slides 17 and 18 have beveled edges 19, which cooperate with the grooveways 16 for the guidance of the slides. The end 20 of each slide 10 is semi-circular in shape, and also beveled in cross section. The slides 17 and 18 are secured, respectively, to crossheads 21 and 22 mounted on piston rods 23 and 24, and held in position by retaining nuts 25. The piston rods 23 and 24 are provided with piston heads 26 and 27, reciprocating in bores 28 and 29 in a cylinder block 30. The outer ends of the cylinder bores 28 and 29 are closed by cylinder heads 31 bolted thereto. The opposite ends of the cylinder bores 28 and 29 are provided with apertures 32 for the passage of the piston rods 23 and 24, and are also provided with glands 33 to prevent leakage around the piston rods 23 and 24.

The cylinder block 30 is bolted to the frame 34, which in turn, is secured, as by the bolts 35, to the side of the casing 10. For the reception of the slides 17 and 18 the end 36 of the frame 34 and the wall of the casing 10 are provided with slots 37 and 38, respectively. The opposite ends 30 of the cylinder bore 28 are provided with pipe connections 39 and 40, the lower cylinder bore 29 being provided with similar connections 41 and 42. The connections 39 and 42 are interconnected by the pipe 43, whereas the connections 40 and 41 are similarly interconnected by the pipe 44. The pipes 43 and 44 terminate in junctions 45 and 46, respectively. These lead, by means of the pipes 47 and 48, to the four-way valve 49 having the operating handle 50 for controlling the valve member 51 thereof. The present invention is not concerned with the details of the valve 49, any suitable valve being used. For example, each slide could be controlled independently with a separate four-way valve, if it is so desired.

When the valve handle 50 is operated to pass pressure fluid through the connections 40 and 41, by way of the pipe 47 into the cylinder bores 28 and 29, the fluid will enter on opposite sides of the piston heads 26 and 27, respectively, forcing them in opposite directions. The piston head 26 will be forced to its extreme left-hand position and the piston head 27 to its extreme right-hand position, as shown in Figure 1. The fluid exhausted from the opposite sides of the piston

- heads 26 and 27 is discharged through the connections 39 and 42 into the pipe 48. Under this action the slide 17 moves to the left, and discloses the opening in the bore 11 of the casing 10. At the same time, the slide 18 moves across the bore 11 and completely closes this bore. The materials may then be dumped in through the aperture in the top of the bore 11, either directly or through the chute 52.
- 10 If the handle 50 is now shifted to reverse the flow of the pressure fluid, the line 48 becomes the pressure line and the line 47 the discharge line. Accordingly, the piston heads 26 and 27 reverse their strokes and return to the opposite positions shown in Figure 1. When this occurs the slide 17 moves to the right to close the top of the bore 11, whereas the slide 18 moves to the left to open a passageway for a measured charge of material to drop into the press, or other apparatus.
- 15 20 The beveled edge 20 on the end of each slide enables the slide to cut its way through any materials, thus cleanly severing the measured portion of the charge from any surplus material which happens to be in the device. If the chute 52 is kept filled with material the alternate motion of the slides 17 and 18 will continue to separate charges and allow them to fall into the apparatus as rapidly as the valve handle 50 is operated.
- 25 In order to prevent the sudden halting of the piston and the slide, and thus prevent vibration and damage to the moving parts, means is provided for causing the pistons to come to a gradual halt. For this purpose, Figure 5, tapered ports 53, 54, 55, and 56 are provided for the passage of pressure fluid to and from the cylinder bores 28 and 29. This construction causes the gradual cutting off of the fluid, with the result of a cushioning action and a gradual halting of the pistons.
- 30 It will be understood that it is desired to comprehend within this invention such modifications as come within the scope of the claims and the invention.
- 35 Having thus fully described the invention, what is claimed as new and desired to be secured by Letters Patent, is:
- 40 45 50 55 1. A charging device comprising a container, a pair of spaced sliding members for selectively opening and closing said container at locations spaced apart from each other a predetermined volume, a piston and cylinder assembly for moving each sliding member, and means for supplying pressure fluid oppositely to said piston and cylinder assemblies oppositely to cause said members to move in opposite directions simultaneously.
- 55 60 65 2. A charging device comprising a container, a pair of spaced sliding members for selectively opening and closing said container at locations spaced apart from each other a predetermined

volume, a piston and cylinder assembly for moving each sliding member, and means interconnecting the opposite ends of said cylinders to cause one sliding member to move in one direction while the other sliding member is moving in the opposite direction.

3. A charging device comprising a container, a pair of movable members for selectively opening and closing spaced apertures in said container and including a predetermined volume therebetween, a fluid pressure motor arranged to move each member, a valve arranged to control the distribution of fluid for said motors, and means arranged to supply pressure fluid oppositely to said motors for causing said members to move simultaneously in opposite directions.

4. A charging device comprising a container, a pair of movable members for closing spaced apertures in said container, a fluid pressure motor arranged to move each member, a valve arranged to control the distribution of fluid for said motors, and means interconnecting said valve and said motors to supply pressure fluid oppositely to said motors for causing said motors to move said members simultaneously in opposite directions.

5. A charging device comprising a container, a pair of movable members for closing spaced apertures in said container, a fluid pressure motor arranged to move said members, a valve arranged to control the distribution of fluid for said motor, means arranged to cause said members to move simultaneously in opposite directions, and means associated with said motors to bring said motors to a gradual halt as said members approach the limits of their motion.

6. A charging device comprising a container, a pair of movable members for closing spaced apertures in said container, a piston and cylinder assembly for operating each member, means for interconnecting the opposite ends of the cylinders of said assemblies, valve means arranged to distribute pressure fluid to said cylinders, and means associated with said assemblies for gradually decelerating the pistons of said assemblies while approaching the extreme limits of their motion.

7. A charging device comprising a container, a pair of movable members for closing spaced apertures in said container, a piston and cylinder assembly for operating each member, means for interconnecting the opposite ends of the cylinders of said assemblies, valve means arranged to distribute pressure fluid to said cylinders, and tapering ports in the cylinders of said assemblies for causing a gradual throttling of the fluid pressure therethrough, whereby to gradually decelerate the pistons of said assemblies while approaching the extreme limits of their motion.

HOWARD F. MACMILLIN.
